Primary Examiner — W. A. Teddy Falloway*Assistant Examiner* — Yuan Yuan(74) *Attorney, Agent, or Firm* — Fish & Richardson P.C.(57) **CLAIM**

The ornamental design for a fidget device, substantially as shown and described.

DESCRIPTION

FIG. 1 is a first top perspective view of a fidget device, showing my design.

FIG. 2 is a front view of the fidget device.

FIG. 3 is a back view of the fidget device.

FIG. 4 is a left side view of the fidget device.

FIG. 5 is a right side view of the fidget device.

FIG. 6 is a top view of the fidget device.

FIG. 7 is a bottom view of the fidget device; and,

FIG. 8 is a second top perspective view of the fidget device. The dashed broken lines shown in the drawings depict environment and form no part of the claimed design.

The dot-dash broken lines define the bounds of the claimed design and form no part thereof.

1 Claim, 6 Drawing Sheets
